UNITED STATES PATENT OFFICE.

CATELLO LONGOBARDI, OF SCHENECTADY, NEW YORK.

DESIGN FOR A MUSICAL INSTRUMENT.

45,566.

Specification for Design.

Patented Apr. 7, 1914.

Application filed February 14, 1914. Serial No. 818,806. Term of patent 14 years.

To all whom it may concern:

Be it known that I, CATELLO LONGOBARDI, a citizen of the United States, residing at Schenectady, in the county of Schenectady and State of New York, have invented a new, original, and ornamental Design for a Musical Instrument, of which the following is a specification, reference being had to the accompanying drawing, forming a part thereof.

Figure 1 is a top plan view of a musical

instrument or mandolin embodying my invention, Fig. 2 is a side elevation of the same, and, Fig. 3 is a bottom plan view of the same.

I claim:

The ornamental design for a musical instrument, as shown.

CATELLO LONGOBARDI.
